UNITED STATES PATENT OFFICE.

EDWARD A. MARSH, OF NEWTON, MASSACHUSETTS.

MACHINE FOR DRILLING AND TAPPING WATCH-BALANCES.

SPECIFICATION forming part of Letters Patent No. 357,398, dated February 8, 1887.

Application filed October 18, 1886. Serial No. 216,492. (No model.)

To all whom it may concern:

Be it known that I, EDWARD A. MARSH, of Newton, in the county of Middlesex and State of Massachusetts, have invented certain new and useful Improvements in Machines for Drilling or Tapping Watch-Balances, of which the following is a specification.

The balance-wheels of the better grades of watches are composed of a body of steel forming the arms and a portion of the rim; but the steel rim is surrounded by a band of metal of much greater expansive quality than steel when subject to the action of heat. The employment of the two metals causes the balance to be self-adjusting, so that when the action of heat shall have expanded the balance the peculiar construction of the rim will cause it to bend inwardly toward the center of the wheel, so that the weight of the rim shall be carried nearer to the center of motion than when the balance is not expanded. The object of this construction is to compensate for the varying length of the hair-spring induced by changes of temperature. To render this compensation more nearly perfect, it is the practice to make a series of screw-holes at intervals around the rim and to insert therein small screws with somewhat heavy heads. These holes have hitherto been made singly by a drill and afterward tapped or threaded singly by a tap, the balance being held on a spindle provided with an index to govern the position of the balance in relation to the drill or tap. One hole only has been drilled at a time, so that the time required to complete the drilling of a single balance would be the time required for one hole multiplied by the total number of holes required—ordinarily about twenty-two.

My invention has for its object to provide a machine capable of drilling or tapping all the holes in a balance-rim simultaneously; and to this end it consists, first, in the combination of a holder adapted to support a balance-rim with a series of longitudinally-movable tap or drill holding spindles arranged radially with relation to said holder, means for rotating said spindles simultaneously, and means for moving them endwise simultaneously to cause the tools held thereby to enter the balance-rim.

The invention also consists in certain combinations of parts in an organized machine adapted only for tapping previously-drilled

holes, whereby the direction of rotation of the spindles is automatically reversed, when the tapping of the holes is completed, to withdraw the taps from the holes.

The invention also consists in the means employed for stopping the operation of the machine after the withdrawal of the taps from the balance, all of which I will now proceed to describe.

Of the accompanying drawings, forming a part of this specification, Figure 1 represents a longitudinal vertical central section of a balance-tapping machine embodying my invention. Fig. 2 represents a section on line $x-x$, Fig. 1. Fig. 3 represents a section on line $y-y$, Fig. 1. Fig. 4 represents a sectional view of a part of the balance-holder and of a balance thereon, and a side view of a part of one of the spindles and a tap therein. Fig. 5 represents a top view of a balance in which screws have been inserted. Fig. 6 represents a section on line $z-z$, Fig. 1, and a plan view of that portion of the machine which is located below the plane of said line. Fig. 7 represents a plan view of a machine organized for drilling the holes preliminary to the tapping operation performed by the machine represented in the preceding figures. Fig. 8 represents a section on line $x'-x'$, Fig. 7. Figs. 9, 10, and 11 are detailed views of an automatic stop-motion used in a machine for drilling. Fig. 12 is an enlarged section of one of the tap-spindles, showing the yielding end which receives pressure from cam g .

The same letters of reference indicate the same parts in all the figures.

In describing my invention I will first refer to Figs. 1, 2, 3, 4, 5, and 6, which represent it as adapted to perform the operation of tapping previously-drilled holes, and will afterward describe the invention as applied to a machine organized only for drilling.

In the drawings, a represents the circular bed or frame of the machine, in the center of which is located a vertical stud or balance-holder, b , which is vertically adjustable in a socket, c , affixed to the bed a . The means here shown for adjusting the stud b are a screw, d , passing loosely through the bottom of the socket c and engaging with a tapped orifice in the bottom of the stud b , and a spring, e , located under the stud and pressing the latter

upwardly as far as permitted by the head of the screw, which is pressed by the spring against the bottom of the socket. The rotation of the screw in one direction will draw the stud downwardly, while the rotation of the screw in the opposite direction will permit the spring to force the stud upwardly. Any other suitable adjusting devices may be employed. The stud *b* has a central orifice which receives a pin, *f*. Said pin enters the central orifice in the arms or cross-bar of the balance *i*, as shown in Fig. 4, the rim of the balance resting on the upper end of the stud and being held thereagainst by a removable cap, *g*.

15 Journaled in bearings in the frame *a* are a series of tap-holding spindles, *h*, radiating from the balance-holding stud *b*, and arranged to present to the rim of the balance the taps which they hold, so as to form threads in a series of properly-arranged holes previously drilled in said rim, the spindles being longitudinally movable, so that the taps are capable of entering and receding from said holes simultaneously.

25 Near the outer ends of the spindles *h*, and on the same axial centers, are located hollow sleeves *j*, on the outer ends of which are formed bevel-pinion *k*, which mesh with a circular rack or ring-gear, *l*, concentric with the balance held on the stud *b*. Said rack or ring-gear is fitted to rotate on a circular seat or bearing on the frame *a*, and has its periphery formed as a spur-gear, which meshes with a smaller spur-gear, *m*, on the main driving and 35 governing shaft *n*.

30 Fitted to rotate on a circular seat or bearing on the frame is a ring, *o*, which is concentric with the ring *l*, and located at a lower plane than the latter. The periphery of the 40 ring *o* is cut as a spur-gear, which meshes with a pinion, *p*, on the driving-shaft *n*. To the upper face of the ring *o* are attached a series of cams or inclines, *q*, the inner edges of which bear against the outer ends of the tap-spindles *h*, and are formed to move said spindles endwise toward the balance-holder *b* when the ring *o* is rotated. The spindles are capable of 45 sliding endwise in the hollow sleeves *j*, and are connected with said sleeves by a groove and feather, or other well-known means, which will insure the rotation of the spindles by the sleeves, and at the same time permit the independent endwise movement of the spindles in the sleeves. The spindles are pressed outwardly or away from the balance-holder by 50 springs *r*, whereby their outer ends are caused to bear with a yielding pressure against the cams or inclines *q*.

55 It will be seen that when power is applied to the driving-shaft, to rotate the same in the direction indicated by the arrow in Fig 6, the rings *l* and *o* will be rotated, respectively, by the gears *m* and *p*. The sleeves *j* and the spindles are simultaneously rotated by the ring *l*, and at the same time the spindles are 60 simultaneously moved inwardly by the cams or inclines *q* on the ring *o*. The taps are thus

simultaneously rotated and caused to enter and thread the holes in the balance-rim until said holes are completely tapped, when the 70 direction of rotation of the driving shaft *n*, rings *l* and *o*, and spindles *h* is reversed, by means hereinafter described, so that the taps are withdrawn from the balance-rim, the 75 springs *r* forcing the spindles outwardly as fast as the backward movement of the taps will permit.

I prefer to provide the spindles with spring-supported terminals *h'*, Fig. 12, which bear directly against the inclines *q* and prevent the 80 spindles from being forced forward into the balance faster than is consistent with the proper performance of their work.

The means for automatically reversing the 85 rotation of the driving-shaft are as follows: The driving-shaft *n* is supported in a vertical position by two arms or bearings, *s s*, projecting from an upright standard, *t*, on the bed-plate of the machine, the lower end of said shaft resting on a step, *u*, in said bed. On the 90 shaft *n*, between the bearings *s s*, are two loose pulleys, *v v'*, on the hubs of which are formed clutch members *v' v'*. Said pulleys are driven in opposite directions by belts or other suitable connections with a prime motor.

95 *w* represents a clutch member adapted both to rotate with and slide on the shaft *n*, between the clutch members *v' v'*, and formed to engage with said members *v' v'* alternately, and thus cause the shaft *n* to be rotated alternately by the pulley *v* and by the pulley *v'*, said pulleys running in opposite directions, as already described, so that the direction of rotation of the shaft *n* is reversed every time the clutch *w* is moved from one pulley to the other.

100 The driving-shaft *n* has cut upon its lower portion a screw-thread, *a'*, of somewhat steep pitch. Upon this threaded portion is a nut, *b'*, having an arm through which passes a guide-rod, *c'*, on which are two adjustable stop-collars, *d' d'*, one on either side of said arm. Below the collars *d' d'* a third collar, *e'*, is affixed to the guide-rod *c'*. To the collar *e'* are pivoted the inner ends of two links, *f' f'*, (see Fig. 2,) the outer ends of which are pivoted to 115 ears formed on two springs, *g' g'*. Said springs are attached at their upper ends to the lower arm or bearing, *s*, in which the driving-shaft is journaled, and their lower ends are free to slip on rests or bearings *i' i'*, supported by the 120 bed of the machine, the springs pressing outwardly against said bearings.

125 The bearings *i'* are preferably cylinders, eccentrically-attached to arms *i''* and capable of being turned so as to vary their lateral positions and thus adjust the pressure of the springs *g' g'*.

130 *k'* represents a rod fitted to slide in guides in the arms *s s*, and having attached to its lower end a slide, *l'*, which is fitted to move on a dovetail guide, *m'*, affixed to the standard *t*. On one side of said slide is formed a dovetail rib or guide, *n'*, on which is fitted to move vertically a smaller slide, *o'*, which is pivot-

ally connected to the meeting ends of the links $f' f'$ and to the collar e' , a single pin serving to connect said links, collar, and slide. To the larger slide, l' , are attached two stops, $p' p'$, one above and the other below the slide o' .

The sliding rod k' has an arm, q' , rigidly connected to it, said arm having a forked outer end which is connected by pins $r' r'$ to half-rings $s' s'$, fitted loosely in the sliding clutch w , the rod k' being thereby enabled to raise and lower said sliding clutch.

The operation of this automatic reversing mechanism is as follows: The springs $g' g'$ at all times exert an inward pressure on the outer ends of the links $f' f'$, which tends to force the meeting ends of said links, and the slide o' connected therewith, either upwardly or downwardly from the position shown in full lines in Fig. 2. When the links are in said position, however, the springs cannot act, but remain inoperative until the said meeting ends are slightly raised or lowered by an upward or downward movement of the rod e' , which is effected by the movement of the nut b' on the threaded portion of the driving-shaft, and throws the links sufficiently out of line to enable the springs g' to press the outer ends of the links inwardly, and thereby raise or lower their meeting ends and the slide o' connected therewith, and cause said slide to strike one or the other of the stops p' on the slide l' , and give said slide, the rod k' , connected therewith, and the sliding clutch member w , connected by the arm q' to said rod, a sudden upward or downward motion, thus disengaging said clutch from one pulley and engaging it with the other. To describe this operation more specifically, suppose the driving-shaft to be in rotation in the direction required to raise the nut b' , and suppose said nut to have pressed the links into the position shown in full lines in Fig. 2. A slight continuation of the upward movement of the nut will throw the links $f' f'$ out of line by elevating their meeting ends, whereupon the springs $g' g'$ immediately act and still further elevate the meeting ends of the links and the slide o' , the links being thus caused to assume the position shown in dotted lines in Fig. 2, and the slide o' being caused to strike the upper stop p' (on the slide l') and raise said slide, the rod k' , and the sliding clutch member w , thus forcing the latter into engagement with the clutch member of the upper pulley, v . The rotation of the driving-shaft n is thus reversed, and the nut b' is caused to move downwardly until its arm strikes the lower collar, e' , and depresses the meeting ends of the links $f' f'$ far enough to enable the springs $g' g'$ to force said meeting ends and the slide o' farther downwardly and cause said slide to strike the lower stop p' , and thus depress the rod and sliding clutch member until the latter engages with the lower pulley, v^2 , and again reverses the rotation of the driving-shaft. In practice, however, I do not allow the downward movement last described to continue until the sliding clutch is

engaged with the lower pulley, v^2 , but, on the contrary, I automatically arrest said downward movement while the sliding clutch is midway between the two pulleys and disengaged from both, thus stopping the operation of the machine for the removal of the tapped balance and the application of another balance to the holder. To this end I provide a spring-actuated stop-pin, t' , which is movable in a socket in the standard t , and is forced by its spring into the path through which the slide l' moves, and arrests the downward movement of said slide and of the sliding clutch connected thereto before the sliding clutch engages with the lower pulley. The operation of the machine is thereby arrested until the pin t' is withdrawn by a suitable lever, u' , whereupon the springs $g' g'$, acting through the links f' and the other intermediate devices, complete the depression of the sliding clutch and engage it with the lower pulley. The operation then continues as above described, the nut b' being raised until the next reversal of the rotation of the driving-shaft, and then depressed until the operation is arrested by the stop-pin. If the stop-pin be held back and not allowed to act, the machine will operate continuously, running first in one direction and then in the other.

It is obvious that my invention is not limited to this particular reversing mechanism, as any other suitable mechanism may be used to reverse the rotation of the spindles.

In a machine organized to drill the holes preparatory to tapping no reversing mechanism is required, as the drills can be readily withdrawn from the holes they have formed.

Such a machine is shown in Figs. 7 and 8, it being similar to that already described so far as the relative arrangement of the spindles h and holder b is concerned; but it has no mechanism for reversing the rotation of the spindles. The ring l is rotated by a belt, a^2 , and the ring o by a worm, b^2 , driven by a belt, c^2 . The spindles h are provided with suitable drills, which are guided in entering the balance-rim by a ring, e^2 , affixed to the balance-holder and concentric with the balance and provided with holes arranged to receive and steady the drills, and thus insure their accurate entrance into the balance-rim.

I provide an automatic stop-motion to arrest the rotation of the ring o after the drilling of each balance, such stoppage occurring when said ring is in the position shown in Fig. 6—that is, after the projecting part of each cam q has passed the end of the spindle last actuated by it—thus allowing the spindle to be pushed outwardly by its spring against the inner portion of the next cam and withdrawing the drill from the balance.

The shaft that carries the worm b^2 is normally loose in the pulley on which the driving-belt c^2 runs, and has a clutch member, a^3 , with which is adapted to engage a sliding clutch, b^3 , which is engaged with and rotated by said pulley. With the sliding clutch engaged a

shipper-bar, c^3 , which is normally pressed outwardly by a spring, d^3 , so as to separate the clutch b^3 from the clutch a^3 , and thus stop the rotation of the worm b^2 and of the ring o . A lever, c^3 , pivoted at f^3 to the bed-plate, bears against a pin, g^3 , on the bar c^3 , and is adapted to be moved by the operator to force the bar back against the pressure of the spring d^3 , and thus engage the clutch b^3 with the clutch a^3 to cause the worm and the ring o to rotate. A spring-latch, f^3 , engages a pin on the shipper-bar, and holds it in the position last described until a pin, k^3 , on the ring o strikes said latch and displaces it, so as to cause it to release the shipper-bar, whereupon the spring d^3 throws it out and stops the ring o , as before. There are as many of the pins k^3 as there are cams q .

I claim—

20 1. The combination of a balance-holder, a series of tool-holding spindles radially arranged with relation to said holder, mechanism for simultaneously rotating said spindles, and mechanism for moving them endwise to present their tools to a balance-rim, as set forth.

2. The combination of a balance-holder, means, substantially as described, for adjusting the same and holding it in any position to which it may be adjusted, a series of tool-holding spindles radially arranged with relation to said holder, mechanism for rotating said spindles, and mechanism for moving the spindles endwise to present their tools to a balance-rim, 35 as set forth.

3. The combination of a balance-holder, a series of tap-holding spindles radially arranged with relation to said holder, mechanism for rotating said spindles, mechanism for moving 40 said spindles endwise to present their tools to a balance-rim, and mechanism whereby the direction of rotation and the direction of the endwise movement of the spindles may be reversed, as set forth.

45 4. The combination of a balance-holder, a series of tap-holding spindles radially arranged relatively to said holder, springs whereby said spindles are normally moved endwise away from said holder, mechanism for rotating said 50 spindles, a ring having a series of cams or inclines adapted to move the spindles endwise toward the holder, mechanism for rotating said ring, mechanism for reversing the rotation of the spindles and the rotation of said ring, 55 whereby the springs are caused to withdraw the taps from the balance, and means for stop-

ping the machine after the withdrawal of the taps, as set forth.

5. The combination of a balance-holder, the series of radially-arranged spindles, the hollow sleeves on said spindles, the ring l , geared to said sleeves, the ring o , having a series of cams or inclines bearing on the outer ends of the spindles, and mechanism for rotating said rings and thereby simultaneously rotating and 65 feeding the spindles, as set forth.

6. The combination of a balance-holder, the series of radially-arranged spindles, the hollow sleeves on said spindles, the springs adapted to press the spindles endwise away from the holder, the ring l , geared to said sleeves, the ring o , having a series of cams or inclines bearing on the outer ends of the spindles, the driving-shaft geared to the rings l o , and mechanism for rotating said shaft in opposite directions, as set forth. 75

7. The combination of the balance-holder, the radiating spindles movable endwise and provided with springs r , the ring l , geared to the spindles, the ring o , having a series of cams, 80 the driving-shaft geared to said rings, the loose pulleys driven in opposite directions on said shaft and provided with clutch members, the sliding clutch member connected, as described, to the shaft between said pulleys, the nut 85 mounted on a threaded portion of said shaft, and devices, substantially as described, intermediate of the nut and sliding clutch, whereby the clutch is moved back and forth between said pulleys, as set forth. 90

8. The combination, with the balance-holder, the radiating spindles, the springs r , and the rings l o , all arranged and operating as described, of the driving-shaft geared to said rings, the loose pulleys driven in opposite 95 directions on said shaft and provided with clutch members, the sliding clutch between said pulleys, the sliding rod k' , connected, as described, to the sliding clutch, the mechanism whereby said rod and clutch are moved 100 alternately in opposite directions, and the spring stop-pin, whereby the movements of the rod and clutch in one direction are automatically arrested, as set forth.

In testimony whereof I have signed my name 105 to this specification, in the presence of two subscribing witnesses, this 11th day of October, 1886.

EDWARD A. MARSH.
